UNITED STATES PATENT OFFICE.

LOUIS STEINBERGER, OF NEW YORK, N. Y.

HIGH-TENSION INSULATOR.

No. 853,744.

Specification of Letters Patent.

Patented May 14, 1907.

Application filed March 28, 1906. Serial No. 308,485.

To all whom it may concern:

Be it known that I, LOUIS STEINBERGER, a citizen of the United States, and a resident of the city of New York, borough of Brooklyn, in the county of Kings and State of New York, have invented a new and Improved High-Tension Insulator, of which the following is a full, clear, and exact description.

My invention relates to insulators, my more particular object being to produce a type of high tension insulator suitable for heavy currents and adapted to prevent arcing from the line to the support under conditions where such arcing might otherwise take place.

I also provide a plurality of supporting portions for the conductor, and also provide means for supporting, simultaneously, a plurality of conductors upon the same insulator.

Among the several objects presented by my invention are the following: 1. To give the insulator a composite structure so that it may be assembled without the necessity for handling pieces of excessive weight; 2. To confer a great amount of mechanical strength by the use of a comparatively small quantity of material; 3. To enable different parts of the insulator to each serve as a complete insulator whenever necessary or desirable; 4. To fit the supporting pin with the lower hood in such manner that the latter rests upon a comparatively broad bearing surface; 5. To provide an insulator having hoods of comparatively large surface, so as to adapt it for supporting conductors carrying currents of very high potential; 6. To provide a number of rests for supporting the conductor or conductors; 7. To make the several parts of the insulator separable so that either of the parts may be readily replaced when injured or destroyed; and to achieve certain other electrical and mechanical objects increasing the general efficiency of the insulator; and 8. To provide an insulator with means for supporting, simultaneously, a plurality of conductors.

Reference is to be had to the accompanying drawings forming a part of this specification, in which similar characters of reference indicate corresponding parts in all the figures.

Figure 1 is a plan view of the insulator ready for use; Fig. 2 is a central vertical section through the same, upon the line 2—2 looking toward the top of the drawings; Fig. 3 is a perspective view of the lower insulator body when removed from the support-

ing pin and disconnected from the upper hood.

The supporting pin is shown at 4 and is provided with a conoidal portion 5 having an annular lower surface 6 and an annular spheroidal upper surface 7, from the center of which projects a vertical boss 8 threaded externally. The insulator body 9 is provided with an annular skirt 9^a and is of such conformity as to fit upon the spheroidal surface 7. The insulator body 9 is also provided with a number of radial supporting ribs 10, each terminating at its upper edge in a flat surface 11, and with an annular skirt 10^d integral therewith. Integral with the insulator body 9 is a boss 12 provided externally with a thread 12^a, and with a slot 14 extending diametrically across its top, as indicated in Figs. 2 and 3. An annular groove 12^b encircles the boss 12 and may be used for retaining a tie wire. A hood 15 is shown at 15 and is provided upon its under surface with an annular channel 16, bounded by an annular bead 17. This bead rests upon the four outer ends 11^a of the radial ribs 10. The hood 15 is provided with a boss 18 integral therewith, this boss having a diametrical slot 19 and being encircled by an annular channel 20, in which the tie wire may be placed. The cable or conductor normally rests in the slot 19 of the hood 15, and is held in position by a tie wire in the groove 20. If, however, this part be broken away or destroyed from any cause, the cable or conductor may rest within the slot 14 of the body portion 9 and be confined by a tie wire in the annular groove 12^b. The ribs 10 are provided with notches 10^a, 10^b, 10^c, into any one of which a conductor may be supported. More than one conductor may be thus supported; as, for instance, in case a number of insulators or insulator pins be disabled by a storm so that several conductors happen to be released. It is also desirable to support several conductors upon the same insulator in instances where some of these conductors are used for absorbing the effects of induction from extraneous wires. The notches 10^a, 10^b, 10^c also increase the surface over which leakage tends to take place, and they therefore diminish the surface leakage. The annular groove 12^b also tends to diminish surface leakage. The supporting ribs 10 are of such conformity that they receive a part of the weight of the hood 15 upon their upper edges 11^a, 11. These supporting ribs

are of such pattern as to distribute the weight of the hood 15 as equally as possible with reference to the insulator body 9.

The hood 15 can by the arrangement above described be made comparatively large and thin without detracting from the dielectric properties of the insulator. The insulator as a whole has considerable mechanical strength and this is due mainly to the disposition made of the material.

The conoidal member 5 is so arranged that its upper or spheroidal surface 7 receives the mechanical strain due to the superimposed weight, in such manner that the strain is distributed as equally as possible. The upper surface 7 so engages the spheroidal surface 9^a of the body portion 9, that in case of a relative movement between these parts the base portion of insulating material will fit neatly upon the surface 7 wherever engaging the same. This arrangement also serves to distribute the strain as nearly equal as possible.

I do not limit myself to the exact form nor to the details of any or all of the parts above shown and described, nor do I limit myself to any particular combination of the parts, nor to the use of any prescribed materials. I prefer, however, to employ the insulating material known in the art as "electrose."

It will be evident to those skilled in the art that many changes in the construction, form, and arrangement of the parts may be resorted to without departing from the spirit or scope of my invention.

Having thus described my invention, I claim as new and desire to secure by Letters Patent:

1. An insulator, comprising a body portion of insulating material provided with supporting ribs projecting radially therefrom, and a hood of insulating material provided with an annular surface for engaging said supporting ribs.

2. An insulator, comprising a body portion of insulating material provided with outwardly extending supporting ribs integral therewith, and also provided with a central boss, and a hood of insulating material provided with a portion engaging said boss and also with portions engaging said supporting ribs.

3. An insulator, comprising a body portion of insulating material provided with supporting ribs, and further provided with a central boss having a thread, and a hood provided with a thread mating said thread of said boss, and further provided with portions for resting upon said supporting ribs.

4. An insulator, comprising a body portion of insulating material provided with ribs integral therewith and extending radially therefrom, said body portion being further provided with a central boss threaded externally, and a hood provided with a

threaded aperture for receiving said threaded boss, said hood being further provided with an annular surface for engaging the outer ends of said supporting ribs.

5. An insulator, comprising a body portion of insulating material provided with a plurality of supporting ribs integral therewith, said ribs being level at the top, and a hood of insulating material secured centrally to said body portion of insulating material and provided with a surface engaging the upper surfaces of said supporting ribs.

6. An insulator, comprising a body portion of insulating material provided with ribs integral therewith and radiating outwardly therefrom, said ribs having surfaces inclined obliquely in relation to said body portion, and a hood resting upon said supporting ribs and connected centrally to said body portion, said hood being provided with means for supporting a conductor.

7. An insulator, comprising a body portion of insulating material provided with a central boss, means for supporting said body portion of insulating material, a hood encircling said boss and provided with projecting portions, and means for bracing said projecting portions.

8. The combination of a body portion of insulating material provided with ribs integral therewith and extending radially therefrom, said ribs being provided with surfaces for supporting conductors, and a hood resting upon said body portion and engaging said ribs.

9. An insulator comprising a body portion of insulating material provided with ribs extending radially therefrom, a skirt mounted upon said ribs and integral therewith, and a hood superposed over said body portion and provided with a surface engaging said supporting ribs.

10. An insulator, comprising a body portion of insulating material provided with a hood, a plurality of supporting portions extending from the upper surface of said hood, means for supporting a plurality of conductors, and means for mounting said body portion.

11. An insulator, comprising a body portion provided with a threaded boss having a slot for receiving a conducting member, and a hood provided with a portion for engaging said threaded boss and also provided with means for supporting a conducting member, out of engagement with said threaded boss.

12. As an article of manufacture, a member of insulating material provided with means whereby it may be supported, said member of insulating material being further provided with supporting ribs extending radially therefrom for engaging a hood, and also provided with a skirt mounted directly upon said supporting ribs and depending therefrom.

13. An insulator, comprising a body portion of insulating material, and a separate hood supported by and covering the said body portion and forming a conductor support, the body portion having auxiliary conductor supports over which the hood extends as a cover.

14. An insulator, comprising a body portion of insulating material, and a separate hood supported directly on and covering the body portion and forming a conductor support, the body portion having auxiliary conductor supports at its outer portion over which the hood extends as a cover, and also a central conductor support beneath and covered by the hood.

15. As an article of manufacture, a body portion of insulating material provided with a threaded boss and with a plurality of rib portions radiating outwardly from said threaded boss, said body portion being further provided with an annular skirt integral with said rib portions and projecting downwardly and outwardly from the same.

In testimony whereof I have signed my name to this specification in the presence of two subscribing witnesses.

LOUIS STEINBERGER.
